(57) **CLAIM**

The ornamental design for a mini bike, as shown and described.

DESCRIPTION

FIG. 1 is a top, front and left side perspective view a mini bike showing my new design;

FIG. 2 is a bottom, rear and right side perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is an enlarged view of detail 9 in FIG. 3;

FIG. 10 is an enlarged view of detail 10 in FIG. 7; and,

FIG. 11 is an enlarged view of detail 11 in FIG. 8.

The dashed broken lines illustrate portions of the mini bike which form no part of the claimed design.

The dash-dot-dash lines in FIGS. 3, 7, 8, and 9-11 indicate the boundaries of the enlarged views and are used for annotative purpose only. They do not limit or define the scope of the claimed design.

1 Claim, 11 Drawing Sheets
